GRAVE MARKING MONUMENT

Filed Dec. 12, 1928

Inventor

John Mathis

By Attorney

UNITED STATES PATENT OFFICE

JOHN MATHIS, OF ST. PAUL, MINNESOTA

GRAVE-MARKING MONUMENT

Application filed December 12, 1928. Serial No. 325,431.

The present invention relates to grave marking monuments.

Grave marking monuments of stone and masonry are so expensive as to prevent their use by a great many people who desire to designate by some means a grave of a departed one.

An object of the present invention is to mark a grave with a suitable monument, the cost of which shall be held within reasonable limits. This application is a continuation in part of abandoned application, Serial Number 700,926, filed March 21, 1924.

In order to attain this object there is provided in accordance with one feature of the invention:

A frame in which is secured a glass plate inscribed with silvered letters with a suitable epitaph, and covered by a protective screen to prevent breakage of the glass plate.

In the accompanying drawings:

Figure 1 is a view in perspective of the device with portions thereof broken away to show details of the construction.

Figure 2 is a vertical transverse sectional view, thru the center of the device shown in Figure 1, and

Figure 3 is a sectional view similar to Figure 2 of a modified form of the device.

Referring to the drawings in detail side pieces 1 are formed with the lower ends thereof pointed so as to facilitate setting the monument in place over a grave. A cross piece 2 is fitted in grooves in side pieces 1, and rods 3 extend entirely thru cross piece 2 to secure it in position. The upper ends of side pieces 1 fit into grooves in a top piece 4 which is secured to the upper end of the side pieces 1 by means of screws, not shown.

A supplementary top piece 5 is securely fastened to top piece 4 as by means of screws, not shown, and a cross 6, or other suitable emblem, may be secured to the supplementary top piece 5 as by means of a mortise and tenon joint, as at 7.

The frame formed by the side pieces 1, the cross pieces 2 and the top piece 4 may be rabbeted out on the front side thereof to form a seat for a glass plate 13 and suitable

boards 9 extend across the frame to form a back therefor, as shown, each board being securely and permanently held in place by a rod 3 passing through a hole drilled longitudinally in the center of each board. A molding 10 extends around the interior of the back of the frame to afford a finish for the edges thereof. Against the face of the boards is fastened, as by gluing, a piece of felt 11, or other cushioning means. A piece of tinfoil 12 may then be secured to the top edge of the frame by any suitable means, and allowed to hang freely over the front of the cushioning means. A plate of glass 13, previously covered on its inner side by a coat of opaque paint and marked with a suitable epitaph by having the opaque paint removed from the letters thereof, is then placed in position as shown. The tinfoil 12 then shows through the letters 14 from which the paint has been removed and makes the letters appear as of silver against a background of opaque paint. A wire screen 15 supported in a frame 16, is inserted in the frame over the glass in a manner to be spaced therefrom, and a decorative molding 17 of a suitable nature is placed around the interior of the frame. The entire frame may then be covered with a coat of good paint to protect it from the weather, the points 18 of side pieces 1 being 70

preferably impregnated with a creosote compound to preserve them from rotting.

A modified form of the device is shown in Figure 3. This construction is similar in all major respects to that shown in Figures 1 and 2 except that in place of the glass and other materials which provide the lettering on the monument, a brass plate 19 which is flanged as at 20 around its edges, is secured in place in the frame provided by cross members 2 and side members 1. The lettering is done directly on this brass plate in a customary manner.

The monument as thus constructed may be secured for a fraction of the cost of a masonry monument, and is easily transported, thereby eliminating large freight charges attendant upon the shipping of masonry monuments. It is to be understood that the construction of the frame is not strictly 95

100

limited to that shown in the accompanying drawing, but one embodying the present invention and covered with a sheathing of sheet copper instead of paint, may be employed.

5 What I claim is:

A grave marking monument, comprising a frame, extensions therefrom to engage a portion of earth and support the monument, frame back members supported by rods penetrating the frame and the back members, a 10 glass plate for an epitaph secured in the frame and having metal-like letters showing against an opaque background, and a metallic screen secured to the frame to cover the 15 glass and be spaced therefrom.

In testimony whereof I affix my signature.

JOHN MATHIS.
